UNITED STATES PATENT OFFICE.

ROBERT OSTERHORN, OF ST. LOUIS, MISSOURI.

DESIGN FOR A PULLEY.

SPECIFICATION forming part of Design No. 17,187, dated March 15, 1887.

Application filed January 24, 1887. Serial No. 225,819. Term of Patent 11 years.

To all whom it may concern:

Be it known that I, ROBERT OSTERHORN, a citizen of the United States, residing at St. Louis, in the State of Missouri, have invented and produced a new and original Design for Pulleys, of which the following is a specification, reference being had to the accompanying drawings, forming part thereof, and which are perspective views of my improved pulley.

Figure I shows my pulley with ribs on the inner face of the rim. Fig. II shows my pulley with brackets at the outer ends of the arms against the rim. Fig. III shows my pulley with both ribs and brackets.

1 represents the rim of the pulley, 2 the hub, and 3 the arms.

4 represents raised ribs or flanges on the inner face of the rim a slight distance from the outer edges of the rim of the pulley.

5 are brackets on the outer ends of the arms against the rim.

The leading features of my design are the raised ribs or flanges and the brackets.

Having thus described my invention, the following is what I claim as new therein and desire to secure by Letters Patent:

1. The design for pulleys herein shown and described, the same consisting of the hub, rim, arms extending from the hub to the rim, and the raised ribs or flanges upon the inner face of the rim.

2. The design for pulleys herein shown and described, the same consisting of the hub, rim, arms extending from the hub to the rim, and the brackets upon the outer ends of the arms against the rim.

3. The design for pulleys herein shown and described, the same consisting of the hub, rim, arms extending from the hub to the rim, the raised ribs or flanges on the inner side of the rim, and the brackets on the outer ends of the arms against the rim.

ROBT. OSTERHORN.

In presence of—
GEO. H. KNIGHT,
Jos. WAHLE.
